UNITED STATES PATENT OFFICE.

ARCHIE G. BRIDGFORD AND SIDNEY B. BOLTON, OF ALEDO, ILLINOIS; SAID BOLTON
ASSIGNOR TO SAID BRIDGFORD.

MANIFOLD HEATER FOR INTERNAL-COMBUSTION ENGINES.

1,427,058.

Specification of Letters Patent. Patented Aug. 22, 1922.

Application filed November 9, 1921. Serial No. 514,023.

To all whom it may concern:

Be it known that we, ARCHIE G. BRIDGFORD and SIDNEY B. BOLTON, citizens of the United States, residing, respectively, at 5 Aledo, in the county of Mercer and State of Illinois, have invented certain new and useful Improvements in Manifold Heaters for Internal-Combustion Engines; and we do hereby declare the following to be a 10 full, clear, and exact description of the invention, such as will enable others skilled in the art to which it appertains to make and use the same.

The present invention relates to a device 15 for heating the manifolds of internal combustion engines and facilitating starting of the same.

An object of the present invention is to vaporize the ordinary fuel for the engine 20 by bringing the fuel into contact with heat and igniting the vapor by an electric current of the usual high tension.

Another object of the present invention is to provide a heater which may be controlled 25 from the instrument board of an automobile, or the like, and which may utilize the electric energy of the storage battery of the automobile for setting the heater in operation.

30 A further object of this invention is to provide a manifold heater wherein the fuel for the engine may be utilized for operating the heater, and wherein means is provided for cutting off the supply of fuel 35 to the heater after the latter has been operated sufficiently to heat the manifold, and to thus prevent waste of fuel after the engine has been started.

The invention still further aims at the 40 provision of a device of this character which may be embodied in the construction of the manifold; which may be installed upon an engine without altering the arrangement and construction of its parts; and which 45 may be quickly and easily connected to the source of fuel supply and to the source of electric energy of the usual automobile.

Our present invention relates to certain apparatus similar to that described but not 50 claimed in our copending application, Ser. No. 525,106, filed Dec. 27, 1921, and entitled Manifold heaters for internal combustion engines.

With the foregoing and other objects in 55 view, the invention will be more fully de-

scribed hereinafter, and will be more particularly pointed out in the claims appended hereto.

In the drawings, wherein like symbols refer to like or corresponding parts throughout the several views,

Fig. 1 is a vertical section, partly diagrammatic, showing a manifold heater constructed according to the present invention.

Fig. 2 is a vertical section taken axially 65 at right angles to the showing in Fig. 1.

Fig. 3 is a side elevation of a portion of the lower end of the casing of the heater.

Referring to the drawings, the body part of the device may be made in the form of 70 an integral casting, as shown, and which has a horizontal pipe or manifold portion 10 adapted to be connected to the side of an engine in the usual manner, and which has an intermediate branch and intake connection 11 which is arranged for connection with a carburetor or other source of fuel supply. Surrounding the juncture of the portions 10 and 11 is a heater casing 12 which extends above and below the manifold and which, at its upper end, is preferably reduced in cross sectional area and rounded to provide an annular flange 13 over which is detachably threaded a cap 14. The cap 14 has a closed top and is preferably provided in its side with a circular row of perforations or vents 15 through which consumed gases and air may escape. The cap 14 also has a reticulated screen 16 80 therein placed below the openings 15, and which is adapted to prevent flame from passing upwardly through the cap.

The lower end of the casing 12 is also reduced to provide an air inlet 17, upwardly 95 through which air may circulate for promoting combustion within the casing. The casing 12 has a large opening 18 in one side which is normally closed by a combined supporting and cover plate 19 held against the exterior side of the casing 12 by removable 100 fastening devices 20, such as screws, as shown in Fig. 3. The plate 19 carries upon its inner side a receptacle 21 which is open at its top and which is arranged to receive a wick 22 of asbestos or other suitable material supported upon a ring or a frame 23 in the receptacle 21. The lower end of the receptacle communicates with a fuel supply pipe 24 which may be formed integrally with the plate 19 and receptacle 21.

Interposed in the fuel supply pipe 24 is a pair of spaced apart valves 25 and 29 providing a measuring chamber 27 therebetween of sufficient size to contain a single 5 charge of fuel from the tank pipe 28 for heating the manifold.

Fitting over the upper end of the receptacle 21 is an electric resistance coil or heater 30 which is encased in a jacket or 10 band 31 of metal or other suitable material, and which at one end is connected to an insulated binding post 32 detachably secured in the cover plate 19 and at its other end is grounded in the receptacle 21. A hood 15 33 surrounds the burner and is spaced about and slightly above the upper end of the receptacle 21. Vapor accumulating at the top of the wick rises in the hood 33 and spreads over the top of the wick 22 in moving upwardly through the casing 12. The plate 19 also carries a spark plug 34 the electrode of which projects into the hood 33 and in slightly spaced apart relation to the top edge of the receptacle 21. When the 20 spark plug is closed in circuit, it is adapted to ignite the gas or vapor in the hood 33. The burning vapor rising through the hood is brought into contact with the top of the wick 22 and consequently the wick is lighted. 25

30 A control rod 35 is mounted in any suitable manner for controlling the closing of the electric circuits, and for controlling the feed of fuel to the receptacle 21. This rod 35 may be connected to a supporting arm 36 carried upon a rod 37 which projects outwardly from the plate 19. The control rod 35 carries a stud 40 which operates in a slot 41 formed in one end of a bell crank lever 42, the other end of which is pivoted 40 to a link 42^a connecting together the arms of the valves 25 and 29, so that when the control rod 35 is pulled in a downward direction, as shown in Fig. 1, the valves will change position. When the valve 25 is 45 closed as shown, the valve 29 is open so that liquid from pipe 28 fills the measuring section 27, and when the valves change position the flow from pipe 28 is cut off and the liquid flows from the section 27 into the 50 receptacle 21 and is raised through wick 22.

The control rod 35 also carries a spring contact 43 arranged to wipe the end of the post 32 and connected to a wire 45 which leads from a source of electrical energy, such 55 as a storage battery 46, the circuit having therein a lamp 48 or other suitable indicator for showing when the circuit through the wire 45 is closed. The indicator or lamp 48 may be grounded as shown at 47. The 60 vibrating coil 50 may be connected by branch wire 44 to the end of the post 32 and include the coil 50 in the circuit when the contact 43 is closed. Also a high tension lead 49 from vibrating coil 50 extends to 65 the spark plug 34.

It is apparent that when the parts are in the position shown in Fig. 1, the post 32 and vibrating coil 50 are closed in the circuit with the battery 46, and the heating coil 30 and is energized and vaporizes the fuel in the hood 33. The vapor rises about the plug 34 and is ignited, the burning fuel lighting the wick 22. As the valve 25 is closed the wick 22 can burn but a short time, or until the supply of fuel in the receptacle 21 is 70 consumed. This period of time, however, is sufficient to thoroughly heat the manifold 10 and accomplish the purpose of the heater. This closing of the valve is also adapted to save fuel consumption which would result 75 in waste through thoughtlessness and forgetting to operate the control rod after the engine was started to extinguish the heater.

After the manifold 10 has been heated to the desired extent, the control rod 35 is 80 drawn downwardly to open the electric circuit and to open the valve 29 and close the valve 25. The receptacle 21 is now replenished with the fuel so that the device is automatically placed in condition for subsequent use. 85

With the foregoing and other objects in view, the invention will be more fully described hereinafter, and will be more particularly pointed out in the claims appended 90 hereto. 95

What is claimed is:

1. In a manifold heater, a casing adapted to embrace a manifold, a burner in the bottom of the casing, a perforated cap closing the upper end of the casing and having a screened partition therein, means for initially lighting the burner, fuel supply means leading to the burner, and a manual control connected to the fuel supply means and to said initial igniting means for alternately energizing the initial means and cutting off the supply of fuel, substantially as described. 100

2. In a manifold heater, a casing adapted to embrace a manifold, a burner in the casing, a vaporizing element in the casing about the burner adapted to heat and vaporize fuel in the burner, means for igniting the vaporized fuel for lighting the burner, a valve controlling flow of fuel to the burner, and a single control element connected to the vaporizer, igniter and the valve for simultaneously closing the valve and heating and igniting the fuel, substantially as described. 110

3. In a manifold heater, the combination 120 of a manifold, a source of electric energy, a casing arranged to embrace the manifold, a burner in the casing, an electric heater for the burner, means for feeding fuel to the burner, whereby the fuel may be vaporized, an electric igniter projecting into close proximity to the burner to ignite the vapor formed thereat, a valve regulating the supply of fuel to the burner, and a single operative element connected to said heater, igniter and 125 130

to said valve for simultaneously operating the same to close said valve when said heater and ignitor are operated, substantially as described.

5 4. In a manifold heater, a casing adapted to embrace a manifold, a battery, a burner, an igniter for the burner, a visual signal disposed between the battery and the igniter, a valve controlling the flow of fuel to the 10 burner, and connections arranged between the valve and igniter for alternately actuating the same to ignite the burner and simultaneously cut off the supply of fuel thereto to prevent burning of the fuel beyond a pre- 15 determined period of time, substantially as described.

5 5. In a manifold heater, a casing adapted to enclose a manifold, a burner in the casing, a fuel supply pipe leading to the burner, a 20 pair of spaced apart valves in said pipe to provide a measuring section therein, means connecting said valves together to alternately open and close the valves, heating means for the burner for vaporizing the fuel there- 25 in, ignition means in the casing for igniting

the vapor, whereby the vapor may light the burner, and operating means for controlling the change of the valves and the operation of the heating and igniting means, whereby predetermined qualities of fuel may be supplied to the burner, and the fuel may be vaporized and ignited, substantially as described. 30

6. In a manifold heater, a casing arranged to embrace a manifold and having openings 35 in its top and bottom, a removable plate closing one side of the casing at its lower end, a burner receptacle mounted on the plate and projecting into the casing, fuel feeding means carried by the plate and connected to 40 the receptacle, a heating device carried by the receptacle for vaporizing fuel therein, a deflector carried by the plate and surrounding the upper end of the receptacle, and igniting means mounted on the plate in proximity to the upper end of the receptacle for 45 lighting fuel vaporized by said heating device.

ARCHIE G. BRIDGFORD.
SIDNEY B. BOLTON.
